SAFETY RAZOR

Michael J. Gray, Duxbury, Mass., assignor to The
Gillette Company, Boston, Mass.

Filed Oct. 2, 1972, Ser. No. 294,481

Term of patent 14 years

Int. Cl. D28—03

U.S. Cl. D95—3 A

Fig. 1

Fig. 2

Fig. 3Fig. 4

FIG. 1 is a perspective view of a safety razor showing my new design;

FIG. 2 is a top plan view thereof;

FIG. 3 is a front elevational view, the back being substantially a mirror image thereof; and

FIG. 4 is a side elevational view, the opposite side being substantially a mirror image thereof.

I claim:

The ornamental design for a safety razor, substantially as shown and described.
